UNITED STATES PATENT OFFICE.

JOHN F. STREIB, OF AVALON, PENNSYLVANIA, ASSIGNEE TO PRESSED STEEL CAR COMPANY, OF PITTSBURGH, PENNSYLVANIA, A CORPORATION OF NEW JERSEY.

ANGLE-COCK HOLDER.

1,202,330.

Specification of Letters Patent. Patented Oct. 24, 1916.

Application filed March 9, 1914. Serial No. 823,332.

To all whom it may concern:

Be it known that I, JOHN F. STREIB, a citizen of the United States, residing at No. 739 Taylor avenue, Avalon, in the county of Allegheny and State of Pennsylvania, have invented certain new and useful Improvements in Angle-Cock Holders, of which the following is a full, clear, and exact description, such as will enable others skilled in the art to which it appertains to make and use the same, reference being had to the accompanying drawings, forming part of this specification.

The object of the present invention is to provide an angle cock holder of simple form, which will, when applied to a car, prevent both the rotation and longitudinal movement of the angle cock, and which will also insure the proper inclination of said angle cock relative to said car.

Referring now to the drawings in which like reference characters refer to like parts and in which—

Figure 1 shows a portion of the end of a car with the angle cock holder mounted thereon; Fig. 2 is a sectional view thereof; Fig. 3 is a detail view of the angle cock holder, and Fig. 4 is a side elevational view thereof.

Referring now in detail to the drawings, 1 indicates an angle cock having the ordinary hexagonal portion 2 to which the train pipe 3 is connected.

4 indicates a portion of an angle cock holder which is preferably in the form of a bracket, having a substantially vertical flange 6 which may be secured to the end portion 7 of a car, and also having a substantially horizontal flange 8, the underside of which is adapted to engage the hexagonal portion 2 of the angle cock and assist in preventing such angle cock from rotating. The flange 8 is provided with a downwardly depending portion 9 which is adapted to engage the face 10 of the hexagonal portion 2 of the angle cock, and when in such engagement, will prevent longitudinal movement of the angle cock in one direction, and to prevent longitudinal movement in the opposite direction, a member 11 preferably of U form is provided which passes around the train pipe 3 and is adapted to engage the face 12 of the hexagonal portion 2 of the angle cock, such member 11 being se-

cured to the holder 4 by nuts 13 or any other suitable means.

The U shaped member 11, which forms a portion of the complete angle cock holder, is adapted, when secured to the bracket member 4, to engage the train pipe and as a result clamp one face of the hexagonal portion 2 of the angle cock in close contact with the undersurface of the portion 8 of the holder 4, and when held in such contact will prevent the angle cock from rotating.

The flange 6, hereinbefore described as being vertical, may be of any other form suitable for application to the end of a car of a type different from that shown in the drawings. This flange 6 may also extend horizontally and be secured to the lower flange of the end sill of a car.

It will be seen from the foregoing description that the holder 4 may be of pressed, forged or cast metal or may be formed from a Z bar of rolled, or built up section.

Having thus described my invention, what I claim as new and desire to secure by Letters Patent is:

1. The combination with a train pipe of an angle cock on said pipe, a bracket adapted to engage the head of said angle cock, a bolt engaging said train pipe for holding said head in close contact with said bracket and for holding said angle cock against backward longitudinal movement.

2. In an angle cock holder, the combination with an angular member adapted to engage the front and top surfaces of the head of an angle cock, of a vertically disposed U bolt secured to said angular member adapted to engage the rear surface of said head and means for securing said angular member to a car.

3. In an angle cock holder, the combination with an angular member adapted to engage the head of an angle cock and prevent said angle cock from rotating and moving longitudinally, of a vertically disposed U bolt secured to said angular member adapted to engage the rear surface of said head and prevent backward movement of the angle cock and means for securing said angular member to a car.

4. In an angle cock holder, the combination with an angular member adapted to engage the head of an angle cock to prevent its rotation, of a lug on said angular mem-

- 2
5. The combination with a train pipe, of
 10 an angle cock on said train pipe, a bracket
 adapted to be secured to a car, a bolt carried
 by said bracket adapted to pass around the
 train pipe for holding a flat surface of said
 angle cock in close contact with said bracket
 15 to prevent its rotation, said bolt preventing
 longitudinal movement of the angle cock in
 one direction, and means depending from
 said bracket adapted to prevent movement
 of said angle cock in the opposite direction.
- 20 6. The combination with a train pipe, of
 an angle cock on said train pipe, an angular
 member carried by the car, a downwardly
 depending lug on said angular member, and
 a vertically disposed U bolt carried by said
 25 angular member adapted to engage the train
 pipe for holding a flat surface of said angle
 cock in close contact with said angular member
 to prevent its rotation, said lug and bolt
 being adapted to prevent longitudinal move-
 30 ment of said angle cock.
7. The combination with a train pipe, of
 an angle cock on said train pipe, an angular
 member adapted to be secured to a car
 and adapted to engage the head of said
 35 angle cock to prevent its rotation, a lug on
- said member adapted to engage the front
 face of said head to prevent longitudinal
 movement of said angle cock in one direc-
 tion, and a bolt carried by said angular
 member adapted to pass around the train 40
 pipe and engage the rear face of said head
 to prevent longitudinal movement of the
 angle cock in the opposite direction.
8. The combination with a train pipe, of
 an angle cock on said train pipe, an angular 45
 member adapted to be secured to a car and
 adapted to hold said angle cock against for-
 ward and rotary movement, a bolt adapted
 to pass around said train pipe for holding
 said angle cock in close contact with said 50
 angular member and against backward lon-
 gitudinal movement.
9. The combination with a train pipe, of
 an angle cock on said train pipe, a bracket
 adapted to be secured to a car, and having 55
 vertical and horizontal bearing faces, a bolt
 carried by said bracket adapted to surround
 said train pipe for holding flat surfaces of
 said angle cock in close contact with said
 bearing faces to prevent forward and rotary 60
 movement of said angle cock, said bolt hold-
 ing said angle cock against backward move-
 ment.

In testimony whereof I affix my signature
 in presence of two witnesses.

JOHN F. STREIB.
